UNITED STATES PATENT OFFICE.

CHARLES B. DAVIS, OF NEW YORK, N. Y.

METHOD OF PURIFYING CARBOHYDRATE SOLUTIONS, ETC.

No Drawing.

Application filed February 21, 1923. Serial No. 620,490.

While the essential features of my invention are applicable to the electrical coagulation and precipitation of impurities in carbo-hydrate solutions generally, I herein by way of exemplification, consider and describe them, mainly, as appertaining more particularly to the treatment of saccharine solutions for the purpose of eliminating, in a simple and inexpensive manner, the coloring matter, etc., contained therein, so as to render the final sugar product pure and white at a nominal cost as compared with methods of sugar refining heretofore known in the art.

With this understanding, the distinctive feature of my invention consists in effecting coagulation and precipitation of deleterious matter from solutions containing carbo-hydrates, and especially from sugar held in solution, by the introduction into the solution, in suitable proportions, of colloids of opposite electrical polarity to effect the neutralization of the colloids initially present in the solution;—an incidental feature in this connection being the specific use of a colloidal tannate of iron, an extremely active colloid for the purpose, all as hereinafter fully set forth.

When a soluble tannate and a soluble iron salt (both crystalloids) are brought into contact with each other, a soluble active colloidal solution of tannate of iron is produced possessing a negative charge of electricity. The iron and tannin are now microscopically divided into particles consisting of atoms together with molecules and ions forming what is called a "micell" which is electrically charged. If this comes into contact with a positive charged colloid such as the yellow colored constituent of raw sugar or syrup, it causes it to coagulate and can now be removed by filtration, due to the fact that the two charges of electricity (electronic action) have become neutralized and are no longer in the colloidal state.

Heretofore, in sugar refining particularly, the elimination of coloring matter and impurities from the saccharine solution preparatory to crystallization has been a difficult and tedious problem, necessitating various preliminary steps and operations, and rendering a pure white product comparatively and proportionately expensive.

By my invention, which is the outcome

of extended scientific research and experimental investigation of the subject, I am enabled to attain the desired result by practically a single operation, thereby saving time and labor in manipulation, simplifying the apparatus involved, and reducing cost of manufacture to an extent equivalent, approximately, of from five to ten per cent per pound of product. Incidentally I thereby also economize space and increase the capacity of a refining plant, considered in a unitary sense, which is likewise an important factor as related to cost of production.

In a majority of cases the colloids contained in solutions of the character designated, are of positive electric polarity (although not necessarily so for reasons hereinafter stated) so that in exemplifying my process it will be convenient to consider treatment of the solution to be decolorized and purified by the introduction thereinto of colloids of negative electric polarity, with the understanding that I do not limit my invention in this respect.

Thus, for convenience of illustration, I will indicate the preferred treatment of one ton of raw sugar dissolved in water to a density of 30° Baumé. To this slightly acid solution three and one-half grams, or about one eighth of an ounce, of a colloidal tannate of iron may be added, together with about one pound of diatomaceous earth, and the whole heated to about 160° F. As a consequence of this admixture, the colloidal coloring matter and impurities of positive electric polarity contained in the solution will be coagulated and precipitated by the electro-negative colloidal character of a colloidal tannate of iron, so that by passing the heterogeneous resultant through a filter press or bag filter the insoluble precipitated coloring matter and impurities held in suspension in the syrup will be segregated therefrom, and on passing this through a char filter, gives a water white liquid which yields a solution of pure, white liquid, which on boiling in a vacuum pan, etc., gives perfectly refined, crystalline sugar of the highest commercial grade and value.

Since raw sugars vary in color content, of intense tinctorial power, and impurities, the quantity of colloid of opposite electric polarity to be added to the solution must be in proportion to the initial colloids contained

therein, as less or more than the requisite equivalent would prevent coagulative action. Hence, the importance of ascertaining the proper quantity of colloid of opposite electric polarity to be added to a saccharine solution to be thus treated, which may be accomplished in the following manner.

For instance, to ascertain the requisite amount of negative colloid to be added to the aforesaid colloidally opposite solution of one ton of sugar, the following means and formula may be utilized.

(A) Six glass tubes, four feet long by about $\frac{7}{8}$ inch inside diameter and drawn out to $\frac{1}{2}$ inch bore at one end, are supported in a stand and each partly filled with 100 grams uniform char of 20/40/60 mesh, and having a piece of cotton wool in bottom to hold the char in place.

20 (B) 700 grams raw sugar and 500 grams

water together with 25 grams kieselguhr, is heated to 160° F. until all sugar is in solution, and then filtered clear.

100 cc. of this 30 Baumé liquor contains 25 70 grams sugar.

157 cc. of this 30 Baumé liquor contains 110 grams sugar.

(C) Into a glass stoppered 100 cc. graduated cylinder, run 10 cc. water followed by 1 cc. each of 5% tannic acid and 5% ferric 30 chloride. Mix and immediately dilute to 100 cc.—(C).

100 cc. (C) contain 2 cc. of 5% of negative colloid.

100 cc. (C) contain 0.1 gram of negative 35 colloid.

1.6 cc. (C) contain 0.0016 gram of negative colloid.

1.6 cc. (C) in 157 cc. (B) or 110 grams 40 sugar—

$$110 \text{ or } 1100000. \quad \left. \begin{array}{l} 0.0016 \\ 16 \end{array} \right\} \text{ equals } \frac{1}{32} \text{ lb. per ton sugar or 14 per million.}$$

(1) 1.6 cc. (C) in 157 cc. (B) 32th lbs. per ton, or 14 parts per million. (Grams per ton).

45 (2) 0.8 cc. (C) in 157 cc. (B) 64th lbs. per ton, or 7 parts per million. (Grams per ton).

(3) 0.4 cc. (C) in 157 cc. (B) 128th lbs. per ton, or 3.5 parts per million. (Grams per ton).

50 (4) 0.2 cc. (C) in 157 cc. (B) 256th lbs. per ton, or 1.75 parts per million. (Grams per ton).

(5) 0.1 cc. (C) in 157 cc. (B) 500th lbs. per ton, or 0.88 parts per million. (Grams per ton).

55 (6) 0.05 cc. (C) in 157 cc. (B) 1000th lbs. per ton, or 0.44 parts per million. (Grams per ton).

With tannic acid at 100 cents per lb., ferric chloride 25 cents per lb., and using 1000th lb. colloid per ton, we have—

100	1000	0.100 cent
25	1000	0.025

65 0.125 cent per ton to treat the sugar.

Six portions of 157 cc. are treated with 1, 2, 3, 4, 5 and 6 amounts of the colloid, mixed and run into the char tubes. On complete drainage, the tube giving the lightest or white liquor, contains the proper amount of colloid per ton to be added.

I prefer to use iron-blue tannin, but the iron $\frac{1}{2}$ green type, and also other metals, as 75 bismuth, manganese, as well as purely inorganic colloids, etc., may also be used. A colloidal tannate has no chemical or invertive action on the sugar.

If the solution to be purified contains 80 either soluble iron or tannin, these should be converted first into an active colloidal tan-

nate of iron by adding thereto a soluble tannate or iron salt respectively, before determining and adding the required amount of negative colloid to remove the colloid of opposite sign, namely the yellow colloid of raw sugar. This yellow colloid is partly produced by a mould growth.

With this process of refining sugar, the present method of defecating with lime and phosphoric acid, which form dark coloured glucosates and result in lowering the purity of the sugar solution, is entirely done away with, simply a treatment with this colloidal tannate of iron or negative colloid (mineral 95 organic salt) and filtration immediately with or without kieselguhr, with subsequent char treatment, is all that is required to produce white liquors.

Since some raw sugars are acid and others 100 alkaline in reaction, the colloidal tannate of iron in acid liquors react as negative colloid, while the same colloidal tannate in alkaline liquors reverses its charge and becomes a positive colloid. In the alkaline state the 105 colloidal tannate splits up, the iron forming a basic condition with basic action, and therefore possesses the positive colloidal property.

Examples:—

(A) Fibres in alkaline solution are negative 110 and precipitate the yellow color.

Fibres in acid solution are positive and will not precipitate the yellow color.

(B) Hydrated ferric oxide in colloidal state is positive in acid solution, while in 115 alkaline solution, its charge or electric sign, is negative.

For the above reason the colloidal tannate of iron is only an example of a colloid of opposite sign, I may use either negative or positive colloids according as the reaction 120 of the liquors vary.

The yellow or other coloring matter being usually in combination with other impurities in solution, such as bacteria, yeast, moulds, albumins, gums, pectin, polyphenols, 5 phenolcarboxylic acids, catechol, oxidases, chlorophyll, wax, fat, essential oils, resins and mineral salts (ash), on precipitation, also carry down these interfering bodies, and this is partly the cause of the resulting pure 10 white liquors above described.

What I claim as my invention and desire to secure by Letters Patent is:

1. The method herein set forth of eliminating impurities from solutions containing carbo-hydrates consisting in the neutralization of the electro-positive colloids by the introduction into the solution of tannate of iron as a colloidal sol, and then passing the same through decolorizing char. 15
2. The method herein set forth of eliminating impurities from solutions containing saccharine matter, consisting in the neutralization of the electro-positive colloids by the introduction into the solution of tannate of iron as a colloidal sol, and then passing it through decolorizing char. 20
3. The method herein set forth of coagulating and precipitating impurities from solutions containing carbo-hydrates, consisting in neutralizing the colloids initially present therein by the introduction into said solution, of tannate of iron as a colloidal sol, substantially as and for the purpose specified. 25
35. 4. The method herein set forth of coagulating and precipitating impurities held in a carbo-hydrate solution, consisting in neutralizing the colloids of a positive polarity

initially present therein by the introduction into said solution of tannate of iron as a 40 colloidal sol, substantially as and for the purpose specified.

5. The method herein set forth of coagulating, precipitating and eliminating impurities held in a carbo-hydrate solution, 45 consisting in neutralizing the colloids of a positive polarity initially present therein, by the introduction into said solution of tannate of iron as a colloidal sol, and then passing the same through decolorizing char, substantially as and for the purpose specified. 50

6. The method herein set forth, of coagulating, precipitating and eliminating impurities held in negative solution, consisting in converting tannate already in solution 55 into active colloidal sol of tannate of iron by adding thereto a soluble iron salt thereafter which neutralizes the positive colloid present, and then passing the same through decolorizing char. 60

7. The method herein set forth, of coagulating, precipitating and eliminating impurities held in a carbo-hydrate solution, consisting in converting iron already in solution into active negative colloidal sol of tannate of iron by adding thereto a soluble tannin salt which neutralizes the positive colloid present, and then passing the same through decolorizing char. 65

8. The improvement in purifying carbo- 70 hydrate solutions which comprises forming within said solutions tannate of iron as a colloidal sol, and then passing the same through decolorizing char.

CHARLES B. DAVIS.
